UNITED STATES PATENT OFFICE

ALF N. LARSEN, OF OGDEN, UTAH

LANDING SKID FOR AEROPLANES

Application filed March 20, 1930. Serial No. 437,468.

This invention relates to aeroplanes and has special reference to landing skids for aeroplanes provided also with landing wheels so that the landing gear may be used either for solid ground or for ice and snow.

One important object of the invention is to improve the general construction of the landing gear in aeroplanes.

A second important object of the invention is to provide an improved arrangement to landing skids or skis mounted for swinging into and out of operative position.

A third important object of the invention is to provide improved and novel means for moving the skids or skis into and out of operative position.

A fourth important object of the invention is to provide means for so moving the skids operable by the pilot and arranged to move the skids simultaneously.

With the above and other objects in view, the invention consists in general of certain novel details of construction and combination of parts hereinafter fully described, illustrated in the accompanying drawings and specifically claimed.

In the accompanying drawings like characters of reference indicate like parts in the several views, and:—

Figure 1 is a front elevation of a portion of the landing gear and its control;

Figure 2 is a side elevation of the parts shown in Figure 1 with the skids raised;

Figure 3 is a view similar to Figure 2 but showing the skids in position for use;

Figure 4 is an enlarged detail section on the line 4—4 of Figure 1;

Figure 5 is a section on the line 5—5 of Figure 4; and

Figure 6 is a section on the line 6—6 of Figure 5 to enlarged scale.

In the drawings accompanying this specification, there is shown only those portions of the aeroplane landing gear which are directly connected with the invention and as here shown these parts include a hollow axle 10 carrying the usual landing wheels 11 and braced to the fuselage of the aeroplane by struts 12.

In order to carry out the invention the

hollow axle 10 is transversely expanded in its central portion and movable longitudinally in said axle are a pair of rack bars 15 having upwardly facing horizontal rack teeth 14 at their outer ends. The middle sections 15 of these bars are offset laterally and are provided with reduced and overlapping end portions 16 having vertical rack teeth 17 on their confronting faces. A gear 18 positioned centrally of the axle meshes with the teeth 17 on both sides. A vertical shaft 19 is keyed or otherwise secured to this gear and extends up into the cock-pit of the aeroplane, being there provided with a hand wheel 20. Fixed to the axle 10 adjacent each end is a horizontal bearing bracket 21 in which is journalled a skid shaft 22 having a gear 23 formed centrally thereof and meshing with the teeth 14 of a respective rack bar. The ends of the shaft 22 project from the ends of the bracket 21 and have skid arms 24 fixed thereto. These arms carry a skid or ski 25 at their free ends and are of sufficient length so that, when the arms are swung to bring the skids into use the latter will lie as shown in Figures 1 and 3, below the wheels 11. When oppositely swung the arms raise the skids to the position shown in Figure 2 and in dotted lines in Figure 1. These movements are effected by turning the wheel 20 which causes the gear 18 to move the rack bars in or out and thus actuates the shafts 22 through the gears and consequently swings the arms 24 and moves the skids as desired.

There has thus been provided a simple and efficient device of the kind described and for the purpose specified.

It is obvious that changes may be made in the form and construction of the invention without departing from the principles thereof. It is not, therefore, desired to confine the invention to the exact form herein shown and described but it is desired to include all such as come within the scope claimed.

Having thus described the invention, what is claimed is:—

1. In combination with aeroplane landing gear including a shaft and a pair of landing wheels journalled thereon, bearing brackets fixed to the axle adjacent its ends, rock shafts

supported in the respective bearings, skid arms fixed to respective rock shafts, skids carried by said arms, a pilot's control wheel, and means operatively connecting the wheel and shafts to operate the latter simultaneously.

2. In combination with aeroplane landing gear including a shaft and a pair of landing wheels journalled thereon, bearing brackets fixed to the axle adjacent its ends, rock shafts supported in the respective bearings, skid arms fixed to respective rock shafts, skids carried by said arms, a pilot's control wheel, a shaft for said wheel, a gear on said shaft, and 10 rack bars meshing with said gear and geared to said rock shafts.

3. The combination with aeroplane landing gear including a hollow shaft and landing wheels journalled thereon, of a pair of 15 rack bars in said shaft provided with upwardly facing horizontal teeth at their outer ends and laterally spaced inner ends having vertical teeth on their confronting faces, a gear meshing with the teeth on said inner ends, a gear shaft having said gear fixed 20 thereon, a hand wheel at the upper end of said gear shaft, bearing brackets at the outer ends of said hollow shaft beyond said wheels, horizontal rock shafts journalled in said 25 brackets and provided with gear meshing with the horizontal rack teeth, rock arms carried by said rock shafts, and skids carried by the free ends of said rock arms, said rock arms being of such length to permit the skids 30 to lie beneath the wheels in operative position.

In testimony whereof I affix my signature.
ALF N. LARSEN.
